HONING DEVICE

John Hansen, Bettendorf, Iowa

Application March 26, 1956, Serial No. 573,761

14 Claims. (Cl. 51—250)

This invention relates to a honing device and especially to such device as capable of use in honing the several blades of bread-slicing machines, for example.

A typical bread slicer, specifically a slicer of the endless band type, includes a pair of drums rotatable about spaced apart parallel axes and a plurality of endless slicer bands trained about the drums, each band being crossed in the form of a figure eight so as to present at the zone of intersection of the straight runs of the band a pair of cutting edges maintained by appropriate guides in parallel planes normal to the drum axes. The several bands thus present several cutting edges through which loaves of bread are passed along a path cut by the blades, the loaves being thus sliced in accordance with the number of cutting edges involved. These bands have a substantial useful life measured ordinarily by the number of loaves cut before defects begin appearing in the loaves, such as crumbling, "snow," crushing, etc., depending upon the nature of the loaves as to type and texture. When the bands show signs of extreme failure in any of the respects noted, they are usually removed from the slicer and returned to the manufacturer for re-sharpening, which is distinguished from honing because in the re-sharpening process the individual bands are placed on special machines and actually re-ground. Re-sharpening or re-grinding, however, is relatively costly as compared with honing and accordingly operators of the slicer machines in bakeries prefer to postpone re-grinding by honing the bands from time to time to improve the performance thereof until such time as re-grinding is inevitable. For this purpose several types of honing devices have appeared in the industry with varying degrees of commercial acceptance. It is an absolute requirement that the honing device be capable of use while the bands are still installed in the slicer, and for this purpose all such devices include means of one form or another for the mounting thereof on the slicer in the slicing zone or proximate thereto. Some devices are capable of honing only one side of one band at a time, others can hone both sides of a single band and some are designed to hone several bands simultaneously. All operate on the principle of positioning the device and running the slicer, preferably at a relatively slower speed. In addition to the foregoing, the safety factor is important, for an operator using the hone is precariously acceptable as to initial cost, maintenance and performance.

The principal object of the present invention is directed toward the provision of a honing device satisfactorily meeting the above requirements in addition to including several novel and significant attributes. The inventive design features the honing of both sides of a band simultaneously by hones spaced lengthwise of the band or blade, so that the hones respectively contact the blade from opposite sides, in this respect the invention providing for the utilization of the intervening portion of the blade in unsupported fashion so that the blade in the honing zone is capable of flexing to thereby improve the honing characteristic by enabling the band to yield laterally according to the uneven but regular variations in the sides of the

2

cutting edge, at which point it is significant to note that the popular slicer bands are scalloped along their cutting edges and thus present alternate peaks and valleys that differentiate the honing problems from mere sharpening of perfectly straight edges as in ordinary knives.

The invention features also the employment of biasing means for applying a honing pressure to the hones, plus means for regulating the pressure, especially in conjunction with a single actuator that functions also to move the hones back and forth or out of and into honing position. An object of the invention is also to improve the mounting of the device for interchangeability of position on the slicer so as to be movable from blade to blade.

A further object is the provision of a simplified honing device having relatively few working parts and utilizing these few parts to the fullest to produce an in-and-out honing motion combined with a "rolling" honing motion so as to improve the honing characteristics of blades having scalloped cutting edges. A specific object is to employ a reciprocating actuator and to mount the hone carriers, preferably individually, on the actuator for reciprocation therewith but for angular movement relative thereto, together with means biasing the hone carriers angularly so as to apply honing pressure laterally inwardly against opposite sides of the blade, preferably in a blade zone intervening between guides spaced lengthwise of the blade. In another significant aspect, the invention features means combining to regulate the angular pressure of the biasing means and to retract the carriers against the bias of the biasing means.

The foregoing objects, while accomplished in a device intended primarily for the honing of blades of the endless band type, are available in general sameness but in perhaps different degrees in the honing of reciprocating blades.

The foregoing objects and features, along with others of significance, will appear as a preferred embodiment of the invention is disclosed, by way of example in the ensuing specification and annexed sheets of drawings, the several figures of which are described immediately below.

Figure 1 is a plan view of the honing device.

Figure 2 is a rear elevation.

Figure 3 is a section, on an enlarged scale, as seen along the line 3—3 of Figure 2.

Figure 4 is a front elevation, on a reduced scale, of the portion indicated by the line 4—4 in Figure 3.

Figure 5 is an enlarged section on the line 5—5 of Figure 4.

Figure 6 is a section, drawn to an enlarged scale, on the line 6—6 of Figure 4.

Figure 7 is an enlarged fragmentary section on the line 7—7 of Figure 3.

Figure 8 is an exaggerated enlargement of the relationship between a blade, shown in section, and a part of a hone at one side thereof.

A basic part of the slicer machine is shown fragmentarily at 10 in Figure 1 as including a side wall to which the honing device is attached by means of a support comprising a pair of parallel rods 12; although, other means of support could well be provided, particularly in cases in which the basic slicer lends itself to such changes. Hence, the supporting characteristics are intended to be representative and not limiting. Straight sections of several blades are shown at B, it being understood that in the case of an endless band type slicer the omitted portions of the bands are looped around spaced apart parallel drums as aforesaid; or, in a reciprocating slicer, opposite ends of the blades are supported in a reciprocating frame. These details are unimportant, it being significant only that by means of the device to be presently described, the blades may be honed while they are in situ in the machine, regardless of its type.

The blades are shown as being uniformly spaced apart on the order of the thickness of the loaf slices to be cut. Thus each blade runs or travels (as respects the part thereof material here) in a generally upright cutting plane. Here, as in the appended claims, expressions such as "upright," "front," "rear" etc. are used in the interests of convenience and brevity and are not terms of limitation, since the parts may be located otherwise relative to each other.

Each blade shown is of the scalloped cutting edge type, typical, for example, of those shown in the U. S. patents to Hansen Nos. 2,002,812; 2,082,832 and 2,596,851, the cutting edge here being designated by the letter C, scalloped to provide alternate peaks and valleys P and V respectively and, conventionally, beveled at opposite sides as at D, whereby the intersection of the plane of each bevel with the peaks and valleys leaves the respective side of the blade, along the cutting edge C, with uniformly spaced high spots H occurring at the sides of the peaks because of the missing portions of the blade effected by the provision of the valleys B. Consequently, it will be seen that the honing problem presents, on the basis of the nature of the blade alone, certain characteristics not involved in sharpening or honing a simple straight cutting edge; although, as will be hereinafter apparent, the principles here elaborated are beneficial in honing other types of edges.

The support rods are suitably affixed to the slicer part 10 as by brackets, only one of which is shown at 14, it being understood that a similar bracket is afforded at the opposite side of the machine. The rods 12 are transverse to and behind the blades B and accordingly dispose also behind the blades a base or base member made up of a slide 16 and a housing 18. The slide is mounted on the rods 12 by means of bearings 20 so that the base may be shifted lengthwise of the rods and thus may be located relative to any one of the several blades according to engagement of the selected blade by upper and lower guide means 22 and 24 carried at the front open end 26 of the housing 18. Each guide means compromises a pair of closely spaced apart guides of any suitable design adapted to receive the blade rather closely but freely therebetween so as to confine the blade and base against relative lateral displacement. Since the guide means 22 and 24 are spaced apart vertically, it follows that the blade is confined or guided at vertically spaced portions thereof and the intervening zone of the blade is laterally unsupported. As will appear subsequently, the honing operation takes place in this zone or area intermediate the upper and lower guides. The guide members may be removably secured to the upper and lower front portions of the housing 18 as by recessed-head screws 23 (Figure 1), whereby the guide members may be readily adjusted and/or removed and replaced in event of wear.

The housing 18 is mounted on the slide 16 for fore-and-aft movement by means of a dovetail connection including a female part 30 on the slide and a male part 32 on the housing. The purpose of the dovetail connection is to enable the housing to be retracted from its Figures 1 and 3 position and relative to the slide to a rearward position in which the guide means 22 and 24 clear the blade B, so that the base as a whole can be shifted to the next or some other blade, after which the housing is shifted forwardly relative to the slide, with the guide means engaging and locating the base relative to such other blade. During lateral shifting, the base slides lengthwise of the rods 12 via the bearings 20. A stop 34, carried by the rear of the male dovetail part 32 (Figure 3) engages the slide 16 to limit forward movement of the housing and this stop is instrumental for locating the starting positions of upper and lower hones 36 and 38 relative to the blade B. These hones, their mounting and their functions will appear in detail below.

The housing 18 is bell-shaped, having its front end 26 open and having at its closed rear end a coaxial integral

bearing boss 40 bore fore-and-aft to afford a bearing 42 for an actuator member, here in the form of a tubular shaft 44. The bearing 42 constitutes means mounting the actuator on the housing and thus on the base for back and forth movement along a fore-and-aft actuator path, which is here the principle axis of the shaft and which axis lies in the plane of the blade. Stated otherwise, the honing device is symmetrical at opposite sides of an upright median plane which is preferably coincident with the blade plane and the axis is included in this plane. In addition to the fore-and-aft movement, the means provided by the bearing 42 carries the actuator shaft for angular movement about this axis, and a handle 46 on the rear end of the actuator affords means for imparting movement to the actuator. For reasons that will appear below, movement of the actuator shaft, both in reciprocation and in rocking, is under control of angular control means, designated in its entirety by the numeral 48.

This means includes a guide element or slot 50, in the form of a spiral or the section of a helix, provided in the upper portion of the actuator shaft 44, and a follower element comprising the cylindrical end 52 of a threaded stud 54 screwed into a vertically tapped enlargement 56 of the bearing boss 40. Hence, as the actuator is moved forwardly, it receives also a counter-clockwise angular motion (as viewed from in front in Figures 4 and 5); conversely, when the actuator is retracted to its rear position, the actuator turns reversely. Opposite ends of the slot 50 limit both fore-and-aft and angular movement of the actuator. In addition, the follower element is so dimensioned as to fit loosely in the slot, at least in an angular direction, and thereby affords lost motion by means of which the actuator can be rocked selectively in opposite directions independent of fore-and-aft movement. Normally, a clearance is afforded at 58 (Figure 7) for the purpose of achieving the aforesaid rockability of the actuator.

The hones 36 and 38, referred to above but generally, are carried by the actuator for fore-and-aft movement in unison with the actuator as well as for lateral movement relative to the actuator. Broadly, the actuator is included in means mounting the hones on the base or base member. Specifically, the mounting of the hones includes a cup-shaped hub 60 bored at 62 to coaxially receive the front end of the actuator, to which it is pinned by a cross pin 64 (Figure 6) and becomes in effect part of the actuator. The cup shape of the hub is afforded by an annular forwardly facing recess 66 which is divided into a pair of substantially identical arcuate pockets 68 and 70 by a pair of generally diametrically opposed spring anchors 72 and 74. In the embodiment shown, the anchors are separate members secured in the pockets by screws or pins 76 and 78, respectively; although, other constructions are not excluded.

The hub 60 has an integral forward coaxial extension or stub shaft 80 which mounts upper and lower hone carriers 82 and 84 for individual angular movement relative to the actuator and hub and relative to each other. These carriers have at their respective inner ends bored hub portions 86 and 88 for mounting on the hub extension 80, and are recessed at 90 and 92 respectively at their outer ends to afford means for mounting the hones 36 and 38. The forward end of the stub shaft or extension 80 is bored and tapped and receives a retaining screw 94, which includes a washer 96 to suitably retain and journal the hone carriers 82 and 84.

The recesses 90 and 92 of the hone carriers respectively have inclined hone-mounting surfaces 98 and 100, which surfaces converge forwardly and are thus in convergent relation to the median or blade plan. The hones have complementary surfaces and are therefore themselves in forwardly convergent relation to each other and to the blade plane. Mounting of the hones on the carriers is completed by dowels and screws, as at 102 for the hone 36 and 104 for the hone 38.

Although the carriers 82 and 84 are ahead of the hub 60, they respectively have rearwardly projecting ears or spring-receiving portions or members 106 and 108 which loosely enter the respective hub pockets 68 and 70 to afford lugs against which biasing means, here curved compression springs 110 and 112, act, these springs reacting respectively on the spring anchors 72 and 74 to urge the carriers 82 and 84 individually in a counterclockwise direction as seen in Figures 4 and 5. In Figure 5, even though the section line 5—5 on Figure 1 is behind the main parts of the hone carriers, these parts have been shown in broken lines for orienting the structure. Spring retaining studs 114, 116, 118 and 120 are provided respectively on the anchors 72 and 74 and on the spring-receiving members or ears 106 and 108. The biasing action of the springs 110 and 112 is limited by individual stop elements or pins 122 and 124, carried by the hub 60 within the arcuate pockets 68 and 70 and interposed respectively ahead of the ears 106 and 108. These pins limit the angular amount that the carriers can move counterclockwise (Figure 5) relative to the actuator, for reasons that will become immediately apparent.

As described before, the follower pin 52 normally occupies a position in which the clearance 58 occurs between it and the far side of the guide slot 50 when the actuator is retracted or in its rear position. At this time, the carrier ears 106 and 108 are pressed into engagement with the stop pins 122 and 124 by the springs 110 and 112. The design is such that under these conditions, the hones are disposed to engage opposite sides of the cutting edge of the blade with but slight pressure, the amount of pressure desired in this respect and at this point being dependent upon the positions of the pins 122 and 124 relative to the lateral spacing of the hones at their forward ends, the angles and dimensions of the blade and the retracted or starting positions of the hones. With these factors known, the proper relationship may be designed into the honing device. Another factor is the angle of convergence of the hones relative to the blade or median plane, plus the fact that since the hone carriers are mounted on the actuator and since the path of the actuator is its axis, which lies in the median plane, the hone carriers would travel forwardly and rearwardly in paths parallel to said axis except for the effect of the spiraling motion produced by the angular control means 48. If the hones traveled in paths parallel to the actuator axis, they would not hone the sides of the blade, since the sides of the blade at the cutting edge C are convergent in a forward direction as respects the use of the terms "front" and "rear" in this disclosure. Therefore, what is required is the combination fore-and-aft and "rolling" motion of the hones as imparted by the angular control means 48, plus the honing pressure applied by the springs 110 and 112 as limited by the stop pins 122 and 124.

The above may be comprehended by assuming that the hone carriers are rigidly mounted on the front end of the actuator and that the lost motion or clearance at 58 is non-existent. Under these conditions, forward movement of the actuator and carriers will be in unison and will also incur rocking of the actuator and carriers as a unit about the fore-and-aft axis of the actuator because of the means 48. If the angle of each hone to the median or blade plane is exactly equal to the angle of the bevel on the cutting edge at the respective side of the blade, the hone would stroke the blade evenly from rear to front and the same evenness of pressure would occur from front to rear as the actuator is retracted. However, a scalloped blade has no simple or single angle such as that assumed. Instead, the angles to the centerline of the blade vary from peak to peak, being smaller at the peaks, because the bevel D is longer, and larger in the valleys, because the bevel D in that zone is shorter and more sharply inclined.

Figure 8 illustrates the above in somewhat exaggerated fashion, wherein the line x—x represents the centerline or

median plane of the blade B. The angle between this line x—x and the bevel D in a valley V may be termed angle *a*; the angle between the bevel D and the line x—x at a peak P may be termed angle *b*; and the angle of convergence of the hone 36 to the line x—x is angle *c*. In a commercial design, these angles are respectively: 6½, 1½ and 4 degrees. Hence, the hones, starting at the backs of the bevels D and moving forwardly at their 4° angles, could not hone the sides of the valleys and peaks both unless some compensatory movement is designed into the honing device such as that here afforded by the angular control means 48 plus the honing pressure applied by the springs 110 and 112 on the angularly movable carriers 82 and 84. Thus, as the hones move forwardly they also move inwardly, not only because the angle of the slot 50 to the upright median plane through the axis of the actuator is also 4°, but because of the pressure of the springs 110 and 112, and the hones therefore tend to traverse the blade plane, as suggested by the difference between the full-line and broken-line positions of the hone 36 in Figure 8, it being understood that the other hone moves similarly but in the opposite direction, since the hone carriers are spaced above and below the actuator axis as well as being offset laterally to opposite sides of the blade plane.

When the user, by means of the handle 46, moves the actuator forwardly, he will tend to give the actuator a twisting motion in the same direction that motion is imparted by the slot 50 and pin 52, hence using up the lost motion or clearance at 58 so that the same space will now exist at the diametrically opposite side of the pin 52. Since the hones are now in engagement with opposite sides of the blade, the blade in effect yieldingly stops the hones against further lateral movement inwardly, and the stop pins 122 and 124 on the hub 60 thus "gain" angularly on the carrier ears 106 and 108 and hence become spaced respectively from the ears in an advance angular direction so that the springs 110 and 112 are no longer opposed by the pins 122 and 124 but are instead opposed by the blade and are now free to exert their pressure on the hones and also to allow the hones to "float" laterally as the hones accommodate themselves to the configurations of the sides of the blade. It is understood, of course, that the blade is traveling vertically during the honing operation. In a preferred construction, the hones may be impregnated at their blade engaging sides to a depth of one-sixteenth of an inch and after they wear to this point they should be replaced. Accordingly, the lost motion at 58 is also one-sixteenth of an inch, so that as the hones wear the carriers "gain" on the stop pins 122 and 124 until, at the end of the limit, the ears on the carriers engage the pins 122 and 124 and further useful honing cannot be accomplished.

Another function of the stop pins 122 and 124 is to keep the hones spaced laterally apart a sufficient distance, when retracted, to enable them to move into honing position without honing the sides of the blade near its back edge. Thus, the user may turn the actuator reversely, while the hones are retracted, and this will bring the stop pins 122 and 124 in engagement with the respective carrier ears 106 and 108 and in effect angularly retract the carriers to their initial spacing.

The recessing of the springs 110 and 112 in the front of the hub 60 adds to the compactness of the structure and affords a simple method of confining the springs and controlling their action on the hone carriers. Mounting of the hub 60 on the front end of the actuator shaft produces an economical design that may be readily fabricated, assembled and disassembled. The importance of the combined fore-and-aft and rolling motion of the hones has been stressed above. Other features not categorically enumerated will readily occur to those versed in the art, as will modifications in the preferred embodiment dis-

closed, all of which may be achieved without departure from the spirit and scope of the invention.

What is claimed is:

1. A honing device for honing opposite sides of the cutting edge of an elongated flexible blade that runs generally in an upright plane, comprising: a support positioned behind the blade; a base on the support and having front and rear ends respectively adjacent to and remote from the blade; an actuator carried by the base for back and forth movement along a fore-and-aft axis; first and second individual hone carriers mounted on the actuator for angular movement relative to each other and relative to the actuator about said axis, said first carrier extending upwardly to an upper free end at a level above the aforesaid axis and offset laterally to one side of the blade plane, and said second carrier extending downwardly to a lower free end at a level below said axis and offset laterally to the other side of the blade plane; upper and lower hone-mounting means respectively on said upper and lower ends for mounting upper and lower hones to extend forwardly into engagement respectively with opposite sides of the blade at vertically spaced portions of the blade; biasing means acting on the hone carriers and reacting against the actuator for urging the hone carriers to turn about said axis in such direction as to cause said upper and lower hone carriers to move laterally inwardly and thus to apply honing pressure to said opposite sides of the blade via the upper and lower hones; and means for moving the actuator back and forth along said axis to move the hones back and forth across the opposite sides of the blade.

2. The invention defined in claim 1, in which: the actuator carries fixed thereto a coaxial hub having a pair of diametrically spaced spring anchors thereon; and the biasing means comprises a pair of springs respectively acting on the hone carriers and respectively reacting against said anchors.

3. The invention defined in claim 2, in which: said hub has a pair of arcuate pockets therein opening axially to the hone carriers; the anchors are mounted on the hub respectively within said pockets; the hone carriers respectively have spring receivers projecting axially into the pockets respectively in angularly spaced relation to said anchors; and the springs are curved and are respectively received within said pockets, one spring extending arcuately between one anchor and one spring receiver and the other spring extending arcuately between the other anchor and receiver.

4. The invention defined in claim 1, in which: each hone-mounting means has a hone-engageable surface disposed in forwardly convergent relation to the blade plane so that the hone mounted thereby is likewise disposed in forwardly convergent relation to said plane.

5. The invention defined in claim 4, in which: the actuator is carried by the base for angular movement about said axis in addition to said back and forth movement; and angular control means including a guide element the section of a helix and a follower element following said guide element, one element being on the actuator and the other being on the base for effecting turning of the actuator in the direction of the action of the biasing means during forward movement of the actuator and for effecting reverse turning of the actuator during backward movement of the actuator.

6. The invention defined in claim 1, including: guide means on the base for engaging the blade from behind to confine the blade and base against relative lateral movement; the fore-and-aft axis of the actuator lies substantially in the blade plane; and the hone carriers are symmetrically arranged both vertically and laterally as respects said axis.

7. The invention defined in claim 1, in which: the actuator is carried by the base for angular movement about said fore-and-aft axis in addition to said back and forth movement to enable turning of the actuator selec-

tively in the counter to the direction of the action of the biasing means when the hones engage their respective sides of the blades.

8. The invention defined in claim 1, including: stop members carried by the actuator and engaged by the hone carriers under action of the biasing means for limiting lateral inward movement of the hone carriers; means mounting the actuator on the base for angular movement about said fore-and-aft axis in addition to and independently of said back and forth movement; and means for selectively turning the actuator about said axis in opposite angular directions irrespective of the fore-and-aft position of the actuator so that with the hones in engagement with opposite sides of the blade the actuator is turnable about said axis and in the direction of the action of said biasing means so as to move the stop elements in said direction and angularly away from the hone carriers whereby said biasing means applies honing pressure to the blade free of said stop elements and said actuator being turnable in the opposite direction to reengage the stops with the carriers.

9. The invention defined in claim 1, including: means mounting the actuator on the base for angular movement about said axis in addition to said back and forth movement; angular control means cooperative between the base and actuator for imparting advance and reverse turning movement of the actuator respectively during forward and rearward movement thereof so as to respectively incur lateral inward and outward movement of the hone carriers relative to the blade, said control means including a guide element in the form of a section of a helix and a follower element running along said guide element, one of said elements being on the base and the other on the actuator; stop members on the actuator engageable by the hone carriers under action of the biasing means; and said guide and follower elements having provision for limited angular lost motion to enable turning of the actuator independently of the imparted motion of the angular control means so as to regulate the angular positions of the stop portions relative to the hone carriers.

10. A honing device for honing opposite sides of the cutting edge of an elongated flexible blade that runs generally in an upright plane, comprising: a support positioned behind the blade; a base on the support and having front and rear ends respectively adjacent to and remote from the blade; an actuator carried by the base for back and forth movement along a fore-and-aft axis; first and second hone carriers mounted on the actuator for angular movement relative to the actuator about said axis, said first carrier extending upwardly to an upper free end at a level above the aforesaid axis and offset laterally to one side of the blade plane, and said second carrier extending downwardly to a lower free end at a level below said axis and offset laterally to the other side of the blade plane; upper and lower hone-mounting means respectively on said upper and lower ends for mounting upper and lower hones to extend forwardly into engagement respectively with opposite sides of the blade at vertically spaced portions of the blade; biasing means acting on the hone carriers to turn about said axis in such direction as to cause said upper and lower hone carriers to move laterally inwardly and thus to apply honing pressure to said opposite sides of the blade via the upper and lower hones; and means for moving the actuator back and forth along said axis to move the hones back and forth across the opposite sides of the blade.

11. The invention defined in claim 10, in which: the actuator is carried by the base for angular movement about said axis in addition to said back and forth movement; and angular control means including a guide element the section of a helix and a follower element following said guide element, one element being on the actuator and the other being on the base for effecting turning

of the actuator in the direction of the action of the biasing means during forward movement of the actuator and for effecting reverse turning of the actuator during backward movement of the actuator.

12. The invention defined in claim 10, including: means mounting the actuator on the base for angular movement about said axis in addition to said back and forth movement; angular control means cooperative between the base and actuator for imparting advance and reverse turning movement of the actuator respectively during forward and rearward movement thereof so as to respectively incur lateral inward and outward movement of the hone carriers relative to the blade, said control means including a guide element in the form of a section of a helix and a follower element running along said guide element, one of said elements being on the base and the other on the actuator; stop members on the actuator engageable by the hone carriers under action of the biasing means; and said guide and follower elements having provision for limited angular lost motion to enable turning of the actuator independently of the imparted motion of the angular control means so as to regulate the angular positions of the stop portions relative to the hone carriers.

13. A honing device for honing opposite sides of the cutting edge of an elongated flexible blade that runs generally in an upright plane, comprising: a support positioned behind the blade; a base on the support and having front and rear ends respectively adjacent to and remote from the blade; an actuator carried by the base for back and forth movement along a fore-and-aft actuator path aligned with the blade; upper and lower hone carriers mounted directly on the actuator for fore-and-aft movement with the actuator and for movement relative to the actuator transversely of said path; upper hone-mounting means on the upper hone carrier spaced above and laterally offset to one side of said path for mounting an upper hone adapted to extend forwardly into engagement with one side of the blade; lower hone-mounting means

on the lower hone carrier for mounting a lower hone adapted to extend forwardly into engagement with the opposite side of the blade; biasing means acting on the hone carriers and reacting on the actuator for urging the carriers laterally inwardly; and means for moving the actuator back and forth along said actuator path to simultaneously move the hone carriers back and forth along vertically and laterally spaced apart honing paths.

14. A honing device for honing the cutting edge of an elongated blade that runs generally in an upright plane, comprising: a support positioned behind the blade and including a base member having front and rear ends respectively adjacent to and remote from the blade; an actuator member carried by the base for back and forth movement respectively away from and toward the blade; 15 a hone carrier pivoted to the actuator member for back and forth movement in unison with said actuator member and for lateral movement relative to said actuator member; hone-mounting means on the carrier for mounting a forwardly extending hone adapted to engage one side of the blade; biasing means acting on the carrier and reacting against the actuator member for urging the carrier laterally in such direction as to press the hone into the blade; means mounting the actuator member on the base 20 for angular movement about a fore-and-aft axis so that turning thereof about said axis and in the direction of the action of the biasing means acts through the biasing means to move the hone carrier and hone laterally in the aforesaid direction; and angular control means cooperative between the members for turning the actuator member in said direction simultaneously with forward movement thereof and for turning the actuator member in the opposite direction simultaneously with rearward movement thereof.
